UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

TRIMMING MECHANISM.

Application filed July 1, 1921. Serial No. 481,848.

To all whom it may concern:

Be it known that I, RICHARD LESTER WILCOX, a citizen of the United States, residing at Waterbury, in the county of New Haven and State of Connecticut, have invented certain new and useful Improvements in Trimming Mechanisms, of which the following is a specification, reference being had therein to the accompanying drawings.

10 This invention relates to a new and improved trimming mechanism and has for its object, among other things, to provide a machine for trimming blanks that will be most efficient in its operation, and constructed of 15 the fewest possible parts.

The improvements in the details and arrangement of parts will be apparent from an inspection of the accompanying drawings in connection with the description herein- 20 after contained and wherein a preferred embodiment of the invention is disclosed for the purpose of imparting an understanding of the same.

In the drawings,—

25 Figure 1 is a vertical section of a machine for trimming blanks having my improvements connected therewith, taken generally along line 1—1 of Figure 2, which is the center line of operation of the machine.

30 Figure 2 is a fragmentary plan view of the machine such as shown in Figure 1.

Figure 3 is a detail view of a portion of the main driving shaft with some of the parts connected therewith in section;

35 Figure 4 is a cross-sectional view of a portion of the frame of the machine, illustrating therein an elevation of the stripper mechanism; and

Figure 5 is a similar view of the frame, 40 the parts in section being taken generally at substantially a right angle to Figure 4, and upon the line 1—1 of Figure 2, illustrating also another elevation of the stripper mechanism.

45 A machine for trimming blanks of the same general type as that herein shown is disclosed in Letters Patent No. 1,294,993, issued February 18, 1919.

Having more particular reference to the 50 drawings in connection with which like reference characters will refer to corresponding parts, 10 designates the frame of the machine which is supported upon suitable legs 11 and having rotatably mounted therein a

main driving shaft 12 having cranks 13 and 14 connected therewith.

Slidably mounted upon a slideway 15 of the frame 10 and held in place by caps 16 is a main gate 17. On the front of this gate is a punch 18 which rests against a backing plate 19 and is supported in a holder 20, having a horizontal motion in a second holder 21. A clamp 22 secures the holder 20 in a fixed position. Vertical adjustment of the second holder 21 is obtained by means 65 of the adjusting screw 23.

Between the main gate 17 and the rear of the frame 10 is a pair of toggle links 24 and 25, the link 25 abutting against an adjustable abutment 26. As the toggle formed 70 of the links 24 and 25 is made and broken, a reciprocatory movement is imparted to the main gate 17.

Mounted on a slideway 27 in the main gate 17 and held in place by caps 28 is a 75 secondary gate 29. Supported in the main gate 17 and in the secondary gate 29 in line with each other are the pins or rods 32 upon which are journaled the rolls 30 and 31. Carried by the secondary gate 29 is the 80 pusher rod 33, one end of which extends through an opening in the punch 18. This rod is adjustable relatively thereto in any convenient or well known manner.

As operating means for the toggles 24 85 and 25, there is provided a connecting rod 34 which with the link 35 constitutes a second toggle operated by a connecting rod 36 which is connected with the main driving shaft 12 through the crank 13. The link 35 90 is mounted on bearings 37 supported by the frame 10.

Mounted so as to be vertically movable between the rolls 30 and 31 and having contact therewith is the cam 38 which is secured to a connecting rod 39 which is also connected with the main driving shaft 12 through the crank 14.

The cam 38 is provided with the cam faces 40 and 41, these being opposite each other, the former contacting with the roll 30, and the latter with the roll 31. The shape of these cam faces may be varied indefinitely to meet the required conditions and as herein shown the cam faces flare outwardly relatively to each other. Upon the cam face 40 there is a cam shoulder 66 and on the cam face 41, a high point 65, above which the

cam face flares outwardly at a relatively sharp angle.

Connected with the inner wall of the frame 10 substantially opposite the forward end of the gate 17 is a die holder 43 within which is mounted a cutting die 42 and a planishing or finishing die 44. In the rear of the planishing die is a backing plate 45 having an opening 46 therethrough which 10 communicates with an opening 47 through the frame 10. The opening 48 through the die 42 is the same shape as the cross-section of the blank to be trimmed and the opening through the planishing die is also of the 15 same shape, but slightly smaller in its dimensions. Both of these dies operate in a well known manner and the shape of the openings therein may be varied indefinitely, as well as the manner of holding them in 20 position, either separately or relatively. It is not essential, of course, that a planishing die should be used and the same may be omitted if desired.

The operation of the mechanism above described is as follows,--assuming now that a blank, as 49, is placed between the punch 18 and die 42 and in alignment with the openings therethrough, the rotation of the main driving shaft 12 will first straighten 25 the toggle formed by the links 34 and 35, which will, in turn, straighten the toggle formed by the links 24 and 25 to move the main gate 17 to the left of Figure 1. While this is taking place the cam 38 which is 30 operated by the crank 14 on the main driving shaft 12, will also be in motion, but the cranks 13 and 14 are so positioned that the first effect as the main gate 17 moves forward, is to cause a motion of the pusher rod 33 to the right of Figure 1 relatively to the 35 main gate 17, so that, when the punch 18 contacts with the blank, the pusher rod 33 will have been moved within said punch.

The punch 18 forces the blank to the left 40 of Figure 1 and into the die 42. At this time the toggle formed by the links 34, 35, 25 and 24 are approaching their straightened position so that the pressure available for cutting blanks is very great.

50 The adjustment of the parts is such that as shown herein the movement of the punch 18 forces the head of the blank 49 substantially through the die 42, thus trimming the blank to a point that is approximately 55 the top of the head thereof. The adjustment of the movement of the main gate 17 is such that the relative position of the face of the punch 18 and the cutting face of the die 42 may be varied, but as shown herein 60 in the face of the punch 18 in its extreme forward position is stopped either exactly flush with or a slight distance from the face of the die 42, preferably the latter.

65 During the forward motion of the main gate 17, the cam 38 by reason of its cam

faces 40 and 41 holds the outer end of the pusher rod 33 either flush with or just behind, as may be desired, the face of the punch 18.

When the main gate 17 is in its extreme 70 forward position, the cam rolls 30 and 31 are against the lower portion of the cam faces 40 and 41. The continued downward movement of the cam 38 then advances the pusher rod 33 gradually to the left, thus 75 pushing the blank through the die 42 and planishing die 44. At about this time the downward movement of the cam has brought the high point 65 on the cam face 41 against the cam roll 31 which rides over said cam 80 roll bringing the upper portion of the cam face 41 against said cam roll.

As this portion of the cam face curves outwardly at a relatively sharp angle, a very 85 quick and rapid movement is imparted to the pusher rod, after the blank is pushed through the planishing die and drops through the opening 47 into a receptacle conveniently arranged to receive it.

The relative movement of the pusher rod 90 is about as follows:

As the punch 18 moves forwardly the end of the pusher rod 33 is either flush with the face or in rear thereof, as may be desired. After the punch 18 has engaged the head 95 of the blank 49 and advanced the same to a point where the underside thereof is in contact with the cutting face of the die 42 the end of the pusher rod 33 is flush with the end of the punch 18. While pressure is being applied by the punch 18, the face of the pusher rod remains flush with the end of the punch and travels at the same speed. When the punch completes its forward movement the pusher rod, however, continues its movement at approximately the same speed, at 100 this time applying pressure to the blank and pushing it entirely across the cutting edge of the die 42. When the blank is in this position the speed of the pusher rod is accelerated to carry the blank entirely through the opening in the die 42 until it contacts with the planishing die 67 in the rear. Its speed is again retarded until the blank has about 105 passed through the planishing die when its speed is again accelerated to give the blank a kick or push that assists gravity in carrying the blank out and away from the dies. The pusher rod now travels in a reverse direction at a very much increased speed, to 110 clear the open space in front of the die 42 and permit the feeding of a new blank. These several relative speeds are acquired in exact timed relation with the progress of 115 the blank toward and through the dies.

The cam rolls 30 and 31 are maintained in contact with the cam faces of the cam 38 by the springs 64 which are connected at their opposite ends to the posts 63, fixed 120 respectively in the main gate 17 and the 125 130

secondary gate 29. Other means of course may be provided for maintaining this contact aside from the spring mechanism just described.

Preferably I arrange the toggle links 24 and 25 in their operative position so that, just before the pusher rod 33 forces the blank through the die 42, the toggles 24 and 25 are moved beyond the center or broken 10 slightly to draw the main gate 17 to the right of Figure 1. This relieves the pressure on the metal left uncut by the punch 18 and die 42, while the blank is being pushed into the die 42 by the pusher rod 33 and give 15 space for the chip formed by the trimming operation produced from the forcing of the blank into the die 42 by the punch 18.

The planishing die 44 may be lubricated through the opening 67 in a well known 20 manner.

It is common in mechanisms of this character to support the shank of the blank 49 by a quill or other centering device while the same is being passed through the die 42. 25 Such mechanism is not herein shown as it is not a part of my present invention.

Any form of mechanism may be utilized for presenting the blank 49 in a position wherein the axis thereof is coincident with 30 the axis of the opening of the punch 18 and die 42, and therefore I have not shown such mechanism, it being understood that the blanks may be presented in such position either manually or automatically, as desired.

Frequently the chip cut from a blank does not readily free itself and in order to insure a positive clearance of the chip, I have provided a stripper mechanism. This comprises a rock member 50 which is mounted 40 upon a stud 51 fixed in a bracket 52 connected with the frame 10 and having an arm 53 connected therewith which carries a finger 54 upon the outer end thereof, and an arm 55 which is connected by the link 68 with the 45 rock arm 58 journaled upon a stud 59 in the frame 10 and carrying a roll 60 thereon which contacts with the periphery of the cam 61 fixed on the main driving shaft 12. The link 68 is connected with the arm 58 50 by means of the stud 56 and connecting pin 57 and with the arm 55 by a similar stud 69 and pin 70.

A spring 62 connected with the arm 53 and the frame 10 exerts its tension so as to maintain the roll 60 in contact with the cam 61. The shape of the cam 61 and the positioning of the parts is such that when a blank is being moved through the die 42, the upper end 60 of the arm 53 and the finger 54 are in the position substantially as shown in broken lines in Figure 4. That is, the outer end of the finger 54 is out of the path of movement of the punch 18. Immediately, however, that the punch 18 and pusher rod 33 are withdrawn, the finger 54 is caused to move across

the face of the die 42 and clear therefrom any chips that may have adhered thereto.

What I claim as new and desire to secure by Letters Patent, is:

1. In a mechanism of the character described, a pair of tools relatively movable toward and away from each other, a pusher rod for forcing the blank through one of the tools, toggle mechanism for actuating one of said tools, and cam mechanism for actuating 70 said pusher rod, whereby the relative speed of movement of said pusher rod is definitely controlled.

2. In a mechanism of the character described, a pair of tools relatively movable toward and away from each other, a pusher rod for forcing the blank through one of the tools, toggle mechanisms for actuating one of said tools, and means for actuating 75 said pusher rod to give it an accelerated movement during the final portion of its stroke in one direction.

3. In a mechanism of the character described, a shaft having independent cranks forming part thereof, a pair of tools relatively movable toward and away from each other, a pusher rod for forcing the blank through one of the tools, toggle mechanism for actuating one of said tools, and cam mechanism for actuating 90 said pusher rod, said toggle and cam mechanisms being actuated from the independent cranks of said shaft.

4. In a mechanism of the character described, a shaft having a crank thereon, a pair of tools relatively movable toward and away from each other, a pusher rod for forcing a blank through one of the tools, toggle mechanism for actuating one of said tools, and cam mechanism for actuating 100 said pusher rod having a connection with the said crank.

5. In a mechanism of the character described, a pair of tools relatively movable toward and away from each other, a pusher rod for forcing the blank through one of the tools, toggle mechanism for actuating one of said tools, and mechanism comprising in 110 part a cam having two operating faces thereon for actuating said pusher rod having a vertical reciprocatory movement between two parts having motion relatively to each other.

6. In a mechanism of the character described, a pair of tools relatively movable toward and away from each other, a pusher rod for forcing the blank through one of the tools, toggle mechanism for actuating one of said tools, and mechanism comprising in 120 part a cam having two operating faces for actuating said pusher rod, said cam having a vertical reciprocatory movement between two parts that at different times have motion as a unit and relatively to each other.

7. In a mechanism of the character de-

scribed, a pair of tools relatively movable toward and away from each other, a pusher rod for forcing the blank through one of the tools, toggle mechanism for actuating one of said tools, and cam mechanism for actuating said pusher rod comprising an endwise movable cam having faces thereon so shaped that the relative speed of motion of said pusher rod is made variable thereby at different points in its movement, a rotating shaft having a crank thereon, and means for actuating said cam from the crank of said rotating shaft.

8. In a mechanism of the character described, a pair of tools relatively movable toward and away from each other, a pusher rod for forcing the blank through one of the tools, toggle mechanism for actuating one of said tools, and cam mechanism for actuating said pusher rod having two cam faces thereon which flare outwardly relatively to each other for a portion of the length of said cam and one of said faces flaring outwardly at a relatively sharp angle near one end thereof.

9. In a mechanism of the character described, a pair of tools relatively movable toward and away from each other, a pusher mechanism for forcing the blank through one of the tools, and means, as a transversely movable finger, for clearing the face of one of said tools.

10. In a mechanism of the character described, a pair of tools relatively movable toward and away from each other, a pusher mechanism for forcing the blank through one of the tools, toggle mechanism for actuating one of said tools, means, as a transversely movable finger, for clearing the face of one of said tools, and means for actuating said finger from the same shaft that actuates said toggle mechanism.

11. In a mechanism of the character described, a cutting tool, a rotary shaft, stripper mechanism for moving any surplus metal upon the face of said tool, comprising a rock member mounted so as to move upon an axis at substantially a right angle to said shaft, a finger connected with the outer end of said rock member, that travels across the face of said cutting tool, means for actuating said rock member in one direction from said shaft, comprising a cam connected with said shaft, a rock member actuated by said cam, and a link between said rock members, and means for maintaining contact with said cam of the part actuated thereby.

12. In a mechanism of the character described, a pair of tools relatively movable toward and away from each other, a pusher rod for forcing the blank through one of the tools, toggle mechanism for actuating one of said tools, cam mechanism for actuating said pusher rod, a shaft, means for actuating said toggle and cam mechanisms from

said shaft, a rock lever, a finger connected with said rock lever, and means for actuating said rock lever from said shaft whereby in timed relation to the movement of one of said tools it will move across the opening in the other of said tools and strip from the face thereof any chip that may have adhered thereto.

13. In a mechanism of the character described; a pair of tools relatively movable toward and away from each other; a pusher mechanism for forcing a blank through one of the tools that will impart an accelerated movement to said blank after it has passed through said tool.

14. In a mechanism of the character described, a pair of tools relatively movable toward and away from each other; a pusher mechanism for forcing the blank through one of the tools that will travel at different relative speeds during the stroke, one of the speeds being substantially the same as that of the movable tool until the blank has passed the cutting edge of the non-movable tool.

15. In a mechanism of the character described, a pair of tools relatively movable toward and away from each other; a pusher mechanism for forcing the blank through one of the tools that will move at the same speed as the movable tool while in contact with the blank and will continue at approximately the same speed after said movable tool has come to rest and until the blank has passed the cutting edge of the non-movable tool, and will travel at an accelerated speed for a limited distance thereafter.

16. In a mechanism of the character described, a cutting die; a planishing die concentric therewith and adjacent thereto; a punch; means for moving said punch toward the cutting die until the same is either flush with the face thereof or a point approximating the same; a pusher rod within said punch that travels at the same speed as said punch while the same is in contact with a blank between said cutting die and punch, and continues at substantially the same speed after said punch has come to rest and until the blank has passed the cutting face of said cutting die and thereafter continues its movement at an accelerated speed until the blank engages the planishing die when the movement thereof is retarded while the blank is being advanced through the planishing die.

17. In a mechanism of the character described, a cutting die; a planishing die concentric therewith and adjacent thereto; a punch; means for moving said punch toward the cutting die until the same is either flush with the face thereof or a point approximating the same; a pusher rod within said punch that travels at the same speed as said punch while the same is in contact

with a blank between said cutting die and punch, and continues at substantially the same speed after said punch has come to rest and until the blank has passed the cutting 5 face of said cutting die and thereafter continues its movement at an accelerated speed until the blank engages the planishing die when the movement thereof is retarded while the blank is being advanced through the 10 planishing die, and after said blank has substantially passed through said planishing die, travels at an accelerated speed and kicks or pushes the blank so that it may clear the 15 said planishing die.

18. In a mechanism of the character described, a cutting die; a planishing die concentric therewith and adjacent thereto; a punch; means for moving said punch toward the cutting die until the same is either flush 20 with the face thereof or a point approximating the same; a pusher rod within said punch; and means for actuating said pusher rod whereby the same will travel at the same speed as said punch while the same is in 25 contact with a blank between said cutting die and punch, and will continue at substantially the same speed after said punch has come to rest and until the blank has 30 passed the cutting face of said cutting die and thereafter will continue its movement

at an accelerated speed until said blank engages the planishing die when the movement thereof will be retarded while the blank is being advanced through the planishing die, and after said blank has substantially passed through said planishing die, will again travel at an accelerated speed and kick or push the blank so that it may clear the said planishing die, and will thereafter be withdrawn from said planishing 35 and cutting dies at an accelerated speed.

19. In mechanism of the character described; means for trimming a blank, comprising a pair of tools, one of which is movable relatively toward the other, during which time the blank is cut in a plane parallel with the direction of movement of the movable tool, said movable tool stopping its movement before said cut is made entirely across said blank; and means, having 40 a less cross sectional area than that of the blank for moving the blank beyond the cutting edge of the non-movable tool and at the same speed of movement as that of the moving tool and by reason thereof continuing the cut of said non-movable tool 45 entirely across the face of said blank.

In testimony whereof, I have hereunto affixed my signature.

RICHARD LESTER WILCOX.
